UNITED STATES PATENT OFFICE.

ALBERT W. TERRELL, OF NEWPORT NEWS, VIRGINIA.

FLUE CLEANER.

1,414,840.

Specification of Letters Patent. Patented May 2, 1922.

Application filed November 18, 1921. Serial No. 516,101.

To all whom it may concern:

Be it known that I, ALBERT W. TERRELL, a citizen of the United States, residing at Newport News, in the county of Warwick 5 and State of Virginia, have invented certain new and useful Improvements in Flue Cleaners; and I do hereby declare the following to be a full, clear, and exact description of the invention, such as will enable others skilled 10 in the art to which it appertains to make and use the same.

The invention relates to the class of tools for removing scale and incrustation from the inner walls of the flues and tubes of steam 15 and hot water boilers, and which, in operation, are rotated at a relatively high speed, the cutting elements flying outwardly by centrifugal action and automatically adapting themselves to the diameter of the flue or 20 tube operated upon.

The invention provides a tool of the character aforesaid which is effective and reliable for the purpose intended and which embodies rows of cutting elements grouped 25 about a body, each row comprising a number of independent cutting elements and the tool being of such construction as to admit of any one of the cutting elements being readily removed for sharpening or replace- 30 ment.

Other objects and advantages will be apparent and suggest themselves as the nature of the invention is understood.

While the drawings illustrate an embodiment of the invention, it is to be understood that in adapting the same to meet different conditions and requirements, various changes in the form, proportion and minor details of construction may be resorted to without de- 40 parting from the nature of the invention.

Referring to the accompanying drawings forming a part of the application,

Figure 1 is a side view of a flue cleaner embodying the invention,

45 Figure 2 is a longitudinal section thereof,

Figure 3 is a transverse section on the line 3—3 of Figure 1,

Figure 4 is a detail view in perspective of one of the cutting elements, and

50 Figure 5 is a detail view in perspective of the body portion of the tool.

Corresponding and like parts are referred to in the following description and designated in the several views of the drawings 55 by like reference characters.

The tool comprises a polygonal body 1 having axial projections at opposite ends which receive heads or end pieces 2 and 3, respectively. The body 1 may be of any length and comprises any number of sides. 60 In the present instance, the body 1 comprises four sides, each having a half round channel 4 to one side of a medial line to receive the hubs of the cutting elements. The projection 5 at one end of the body 1 is externally threaded to receive the end piece 3 which is formed with a hub or boss 6 designed to receive an operating member such as a rod, bar or shaft. The projection at the opposite end of the body 1 comprises an 70 angular or square portion 7 and a threaded portion 8. The end piece 2 is mounted upon the angular portion 7 and is retained in place by means of a nut 9 mounted upon the threaded portion 8. The end pieces 2 and 3 75 are formed with openings in line with the respective channels 4 of the body 1 to receive the ends of pins 10 or like parts upon which the cutting elements are loosely mounted.

80 The cutting elements are of similar or like formation each comprising a segment portion 11 and a hub 12, the latter receiving the pins or like parts 10. The segment portion 11 is toothed at its outer edge, as indicated 85 at 13. The hub 12 projects laterally and provides an extended bearing for the cutting elements besides serving to properly space the same. The cutting elements of one row have the hubs 12 facing in one direction, 90 whereas the cutting elements of the adjacent rows have the hubs 12 facing in an opposite direction. As a result of this arrangement the cutting elements have a staggered or alternate arrangement to insure every part of 95 the flue or tube being acted upon when the tool is in operation. When the end piece 2 is removed, access may be readily had to any one of the cutting elements, either for sharpening or replacement as required.

100 It is to be understood that the tool is provided in different sizes and by reason of the pivotal mounting of the cutting elements they fly outwardly under centrifugal action thereby adapting the tool for tubes or flues 105 of various sizes within certain limits. When in operation, the tool is rotated at a relatively high speed and at the same time is moved through the flue or tube to be cleaned, the teeth 13 of the cutting elements serving 110

to loosen and detach scale and incrustation from the sides of the flue or tube in a manner readily appreciated.

What is claimed is:

- 5 1. A flue cleaner comprising an elongated polygonal body having longitudinal channels in its sides, pins disposed opposite the several channels, and a plurality of cutting elements having hubs at their inner ends fitting the respective channels and receiving the pins in cooperative relation therewith, the cutting elements of the several rows being spaced apart and having a staggered arrangement.
- 10 2. A flue cleaner comprising an elongated body, pins grouped about the sides of the body, and a plurality of cutting elements pivotally mounted upon each of the pins in spaced relation, each of the cutting elements
- 15 comprising a segment portion toothed at its outer edge and a laterally extending hub, the hubs of the cutting elements mounted on each of the pins facing in the same direction and the hubs of intermediate and alternate

rows of cutting elements facing in opposite 25 directions whereby to give the cutting elements a staggered arrangement.

3. A flue cleaner comprising an elongated polygonal body having axial projections at opposite ends and having the faces of the 30 body channeled to one side of a medial line, end pieces mounted upon the axial projections, pins supported at their ends in the end pieces and disposed opposite the respective channels of the body, and a plurality of cutting elements mounted on each of the pins, each of the cutting elements comprising a segment portion toothed at its outer edge and having a laterally extending hub, said cutting elements being disposed to have a staggered arrangement. 35

In testimony whereof I affix my signature in presence of two witnesses.

ALBERT W. TERRELL.
